UNITED STATES PATENT OFFICE

MICHAEL F. DAVORAN, OF CINCINNATI, OHIO, ASSIGNOR TO THE CRANE & BREED
CASKET COMPANY, OF CINCINNATI, OHIO, A CORPORATION OF OHIO

DESIGN FOR A BURIAL VAULT OR ARTICLE OF SIMILAR NATURE

Application filed December 22, 1930. Serial No. 38,088. Term of patent 14 years.

To all whom it may concern:

Be it known that I, MICHAEL F. DAVORAN, a citizen of the United States, residing in Cincinnati, in the county of Hamilton and State of Ohio, have invented a new, original, and ornamental Design for a Burial Vault or Article of Similar Nature, of which the following is a specification, reference being had to the accompanying drawing, forming part thereof, in which the figure is a perspective view of a burial vault showing my new design. The opposite sides not shown are the same as those shown.

I claim:

The ornamental design for a burial vault or article of similar nature, substantially as shown and described.

MICHAEL F. DAVORAN.
